ABSTRACT OF THE DISCLOSURE

An electronic shift register controlled device for controlling the sorting of documents as they pass through isochrone (equal time) sections of branching channels from the document input of the device. The improvement resides in photoelectric sensing means between each isochrone section coupled with the electronic shift register for detecting errors in the shorting of the documents at the locations which the errors occur.

Related applications

Netherlands priority application Ser. No. 6,407,349, filed June 26, 1964.

Summary of invention

The invention relates to a system for sorting documents, such as letters, which documents are provided with a sorting code in which the discharge points of the letters are chosen by combinations fixed at a central point or station for controlling a number of clack gates or switches in the system.

According to the invention the transport of documents or letters is divided into one main channel and a branch of channel sections, each section and each discharge point or output lying between isochrones, which isochrones are lines between points with equal letter propagation times from a common document input station. Central registers are provided for each channel isochrone section in which the information stored is in accordance with the vertical channel and the discharge gate in that channel which is to be chosen for that document or letter. Since the outputs along the channels are grouped according to isochrones, only one document or letter can be in one channel isochrone section at a time.

In a particular case the dividing system is built up with a horizontal supply-channel with switches into a number of vertical channels, each of which vertical channels has switches and casting-off points for the letters.

The beginning of each isochrone channel section is marked with a photo-electric cell. If the front of a document or letter reaches the beginning of such a section, a photo-electric cell which marks that section, delivers an impulse, which is used to shift the information from the registers belonging to the previous isochrone channel section to the registers of the isochrone channel section in which the front of the document or letter appears.

In a system of this kind jams can occur by jamming of the document or letter. Moreover it is possible that through a disturbance, a switch does not follow the electrical control commands in which case missorting will occur.

With the aid of the impulses of the photo-electric cells which mark the channel sections and of the information in the registers, jams and missortings can be detected. By means of a lamp monitor, adapted for this purpose, the place where a jam or a missorting has occurred, is automatically signalled.

A dividing system with m vertical channels and n

casting-off points per vertical channel operates with a p bit code, generally requiring a shift register with a total capacity of $2 mp + mnp$ bits. If the vertical channels are adjusted in such a way that the casting-off points are on equal height opposite to each other, the necessary register capacity amounts to $2 mp + \frac{1}{2} mnp$ bits. Due to the division into isochrones channel sections, the required register capacity becomes smaller, viz $mp + (m+n)p$ resp.

$$10 \quad mp + \left(m + \frac{n}{2} \right) p$$

bits.

Brief description of views

The above mentioned and other features and objects of 15 this invention and the manner of attaining them will become more apparent and the invention itself will be understood best by reference to the following description of an embodiment of the invention taken in conjunction with the accompanying drawings, wherein:

20 FIG. 1 is a schematic diagram showing an isochrone dividing system according to one embodiment of this invention with a horizontal channel and a number of descending channels, and with a reading station for the scanning of the marks on the document or letter which 25 reading station is followed by a number of shift registers for the control of the switches in said channels;

FIG. 2 shows an enlarged schematic side view of two switches or clack gates in a vertical channel for two casting-off points lying at the same or equal height;

30 FIG. 3 shows a table for the binary metering of the registers with a decimal translation;

FIG. 4 shows a diagram of the signalling lamps for the signalling of jams for a system as shown in FIG. 1; and

35 FIG. 5 is a schematic block wiring diagram of a part of the control and check circuits for the system of FIG. 1.

Detailed description

FIG. 1 shows a horizontal channel h with a number of 40 descending channels $g1$ through $g8$ leading to the outputs, discharge points, or stores. The letters or documents are led one at a time into the channel h after being taken from the stack a by means of a feeding device b and then being led further past the reading device 1. The destination of the letter is indicated on it in code signals and the code signals are scanned with the aid of the reading device 1 and converted into electrical impulses which are stored in two sets of three triggers in the controller circuit S.

With the aid of the controller circuit S the information is checked for validity and temporarily stored in a binary code in its triggers before being shifted through triggers $S1a$ through $S12a$ and $S1b$ through $S7b$ as the document or letter passes one of the diagonally connected isochrone photocells until the correct combination of pulses from the register triggers operates the thus selected switch or clack gate via a circuit similar to that shown in FIG. 5 described later.

When the front of a document or letter passes the first photocell $f1$ in the horizontal channel h , the information from the triggers in the circuit S is carried over into the shift registers $S1a$ and $S1b$. This information is in the binary code, and in shift registers $S1b$ through $S7b$ it selects the desired vertical channels $g1$ through $g8$ in which the letter must be delivered, whereas the information in the shift registers $S1a$ through $S12a$ selects the desired outlet or store via a switch or clack gate in that vertical channel.

When the front of the letter has passed the photo-electric cell $f1$ the letter is in the first diagonal isochrone channel section. Thus terminals of this isochrone channel section are marked by the photo-electric cells $f2$ and $f1.1$; the terminals of the second isochrone channel section are marked by the photo-electric cells $f3$, $f2.1$ and $f1.2$, etc.

The information transport by the shift register can now take place in such a way that, if e.g. one of the photo-electric cells $f3$, $f2.1$ or $f1.2$ is obscured, the information contents of the shift registers $S2a$ and $S2b$ are transported or shifted to the next registers resp. $S3a$ and $S3b$. For the remaining isochrone channel sections this occurs in the same way. The switches or clack gates in an isochrone channel section are connected via a logical circuit with the shift register sections for that isochrone channel section. If e.g. the information contents of shift register section $S1b$ is 001 (thus a binarily coded 1) the clack gate or switch $k1$ will be energized and the letter or document is conveyed into the vertical channel $g1$. If the letter is further destined for the second store in that channel $g1$, the binary information will, at the instant that the photo-cell $f1.1$ is covered by the front of the letter, be forwarded into shift register section $S2a$, which causes the excitation of clack gate or switch $k1.2$.

The sorting process for the remaining destinations takes place in an identical way. A number of documents or letters can be in the outlet channels simultaneously; however, one letter can only be present per diagonal isochrone channel section shown in FIG. 1.

The lower ends of the vertical channels $g1$ through $g8$ are connected with the return channel r . If a document or letter does not find a switch, clack gate, or discharge point on its way in the sorting system so that that letter is brought into a store, this document or letter is transported to the return channel r .

In FIGURE 2 two switches or clack gates lying at the same or an equal height in a vertical channel are indicated. These can be e.g. the clack switches or clack gates $k1.1$ and $k1.2$ of the first vertical channel $g1$ in FIG. 1. These clack gates $k1.1$ and $k1.2$ are drawn in full lines in their unoperated positions, wherein the electromagnets which work them, are not energized. In such a case a document or letter will pass both clack gates and be conveyed further downwards through the vertical channel $g1$.

FIG. 5 shows the part of the control and checking circuit which relates to the third isochrone channel section in FIG. 1. If the front of a letter passes one of the photo-cells $f3$, $f2.1$ or $f1.2$, one of the inputs of the OR-gate $P1$ becomes negative. The output of the converting amplifier or inverter $V1$ then becomes positive which combination forms a NOR-gate $G10$. By means of the AND-gates $P2$ through $P7$, working with the positive polarity, the information from the shift register sections $S2a$ and $S2b$ is transferred into the sections $S3a$ and $S3b$ (the latter two groups of triggers $S2b$ and $S3b$ are not shown in FIG. 5 to reduce its complexity).

It is supposed that a document or letter is destined for the second store in the vertical channel $g2$.

At the moment when the output of the converting amplifier or inverter $V1$ obtains the positive polarity, the binary information 010 appears at the outputs of the registers $S3a$ (and registers $S3b$ also connected to AND-gates $P8$ and $P9$ as are the registers shown), which causes in the AND-gate $P9$, working at the negative polarity, a negative polarity at its output.

Via the converting amplifier or inverter $V3$ the electromagnet of the clack gate $k2.2$ is energized, which causes the letter during the transport through the channel $g2$ to be delivered to the desired first store. If at the output of the registers $S3a$ the information 001 is present, the electromagnet of the other clack gate $k2.1$ at the same level or height is energized via an identical circuit, and letter then delivered in the other or second store at that level.

If one of the electromagnets of the clack gates $k2.1$ or $k2.2$ is energized, the OR-gate $P10$ has a negative output potential. If the photo-electric cell $f2.1$ is covered by the front of the letter, a negative potential impulse will appear at the output of the impulse-shaping network $D1$ with a little longer duration of time than needed for a letter to pass through that isochrone channel section.

If in the above-mentioned example the clack gate $k2.2$ 75

is not in the correct position, the letter will not be delivered in the store but after a certain time, the following photo-electric cell $f2.2$ in the next isochrone channel section will be covered, by which a negative potential appears at the output of that photoelectric cell. In that case a negative potential will appear at the output of the AND-gate $P11$, working at the negative polarity, which potential reaches the OR-gate $P12$ and the converting amplifier or inverter $V4$, or the NOR-gate $G12$. In the output circuit of inverter $V4$, a jam lamp $L2.1$ may be inserted, which will be lighted in the described case to signal that the clack gate $k2.2$ did not operate. The place of the lamp on the monitoring table, which is shown in FIGURE 4, indicates where the fault appears. Also connected to the circuit from the NOR-gate $G12$ may be an emergency switch to stop the whole device.

In the case that a letter must not be delivered in the stores 1 or 2 of the vertical channel $g2$, the OR-gate $P10$ will carry a positive potential at its output. Consequently, 20 a negative potential is at the output of the converting amplifier or inverter $V5$. At the output of the impulse-shaping network $D2$ a negative impulse of short duration will appear at the terminal of the impulse, which impulse is delivered by the impulse-shaping network $D1$. During the presence of the impulse from network $D2$, the letter must have reached the following isochrone channel section; consequently, the output of the converting amplifier $V6$ or NOR-gate $G13$ must carry the positive polarity and the jam lamp $L2.1$ or alarm is not operated. However, if 25 there is a jam, this is not the case and then the output of the AND-gate $P13$ working at the negative polarity becomes negative, by which the signalling lamp $L2.1$ is also lighted again via the NOR-gate $G12$.

Similar circuits are employed for the remaining signalling lamps.

While we have illustrated and described what we regard to be the preferred embodiment of our invention, nevertheless it will be understood that such is merely exemplary and that numerous modifications and rearrangements may be made therein without departing from the essence of the invention.

We claim:

1. A device for sorting documents into a plurality of outlets, said device comprising:
  - (a) means (b) for feeding the documents one at a time into and through said device,
  - (b) means (S) for setting up bits of information in a set of triggers corresponding to said outlets,
  - (c) means (f) for detecting the leading edge of each document fed through said device at substantially equal time-distance intervals throughout said device,
  - (d) a main (h) and a plurality of branch ($g1$ through $g8$) channels from said feeding means for passage of said documents, along which channels said detecting means are relatively evenly distributed and located,
  - (e) a step register means ($S1a$ through $S12a$ and $S1b$ through $S7b$) for said information bits set up in said triggers, which register means is stepped each time a document's leading edge passes one of said detecting means in said channels,
  - (f) switch means ($k1$ through $k8$) for said documents between said main and each said branch channels, and switch means ($k1.1$ through $k8.8$) in said branch channels between each said detecting means for discharging said documents into said outlets,
  - (g) separate electronic gate means ($P8$, $P9$) corresponding to each said switch means and each said information bits, whereby each document is switched into its corresponding outlet when it reaches its said branch channel and its said outlet at its passage through said device, and
  - (h) timing means ($D1$, $D2$, $L1$ through $L8$, and $L1.1$ through $L8.4$) controlled by said detecting means and said gate means for detecting irregularities in the movements of said documents through said device.

2. A device according to claim 1 wherein said detecting means comprises photoelectric cell means.

3. A device according to claim 1 wherein said switch means include clack gates operated by electromagnetic means.

4. A device according to claim 1 including a pair of switch means between each detecting means in each said branch channel.

5. A device according to claim 1 wherein said timing means controls the operation of said gate means when a document is to be delivered at its adjacent output.

6. A device according to claim 1 wherein said timing means for detecting irregularities includes an alarm means.

7. A device according to claim 6 wherein said timing means includes means for preventing the operation of said alarm means when a document must not be delivered to an adjacent output.

8. A device according to claim 1 including a common return channel (r) connected to the ends of all of said branch channels (g1 through g8) beyond said switch means (k1.1 through k8.8) in said branch channels, for receiving any document which has not been discharged into one of said outlets.
